UNITED STATES PATENT OFFICE.

WALTER C. LINDEMANN AND GUSTAVE C. LORENZ, OF MILWAUKEE, WISCONSIN, AS
SIGNORS TO A. J. LINDEMANN & HOVERSON COMPANY, OF MILWAUKEE, WISCONSIN,
A CORPORATION OF WISCONSIN.

LIQUID-FUEL RESERVOIR.

Application filed December 21, 1923. Serial No. 681,943.

To all whom it may concern:

Be it known that we, WALTER C. LINDEMANN and GUSTAVE C. LORENZ, citizens of the United States, and residents of the city 5 of Milwaukee, in the county of Milwaukee, State of Wisconsin, have invented certain new and useful Improvements in Liquid-Fuel Reservoirs, of which the following is a specification.

10 The improvements relate to reservoirs for burners employing a liquid hydrocarbon fuel, and more particularly reservoirs of the well known student lamp type, in which there is an upper tank, with its outlet in a 15 lower receptacle, and in which the level of the fuel is maintained by the sealing of the outlet of the upper tank by the liquid in the lower receptacle. In devices of this character it is essential that the positions of the 20 two parts of the reservoir shall be so maintained as to insure the proper relations between the said parts, and that the accessories and supporting structure shall be of such 25 construction that this relationship shall be maintained under all conditions of use, and protected against accidental disturbance. Reservoirs of this character are employed in connection with burners used for various 30 purposes, and among the uses to which the present improvements are adapted are for oil heating and cooking stoves and brooders.

The improvements are illustrated in the accompanying drawings, in which Fig. 1 is a side elevation of a reservoir and supporting structure, with adjacent parts, more 35 particularly adapted to be used in a brooder; Fig. 2 is a view taken at substantially right angles to the point of view of Fig. 1 and from the right in that figure; Fig. 3 is a side view showing a modification, which may be used for cooking and other 40 stoves; Fig. 4 is a view taken substantially at right angles to Fig. 3 and from the left; Fig. 5 is a view similar to Fig. 3 of a modified form, and Fig. 6 is a view similar to 45 Fig. 4 of the same.

In the drawings, 1 is the upper tank or reservoir, which is in the form of a bottle, and when in operative position has its neck 50 2 with valve controlled mouth 3 projecting downwardly into the lower receptacle 4. It is supported by means of a circumferential boss or bead 5 at about midheight, and a metallic band 6 clamped thereon. A bale 7,

by which the bottle may be conveniently 55 carried is attached to brackets 8 on opposite sides of the band 6.

From the lower part of the bottom receptacle 4 an outlet pipe 9, through which liquid fuel is supplied to the burner or 60 burners, extends, and this pipe has the usual accessories, such as a burner connection 10, a cap 11 closing its outer end and a support 12. It may also have clamp nuts 13 for securing it to the shell or frame of the heating device or stove, and a support 14 connected therewith by a collar near the reservoir. 65

Where the burners are not enclosed within a frame or housing, upon which the oil 70 supply pipe 9 can be rigidly supported the shield and support 15 preferably extends downwardly to a point below the said pipe, and may be attached to the floor, or some other support, by an angle bracket 16, or 75 other suitable connection. It is not necessary however to provide this support for the reservoir in all cases, and particularly where a foot support 14 is employed. Therefore whether the stove is provided with a frame 80 or with a support 14, the supporting shield 15, or either of the shields 15^a and 15^b may be employed. The primary object of all of them is to support the upper tank or bottle firmly and hold it against vertical or lateral 85 movement bodily. To this end it is provided with a reinforcing strip or band 22 secured to its upper edge and extending around the bottle 1 and with a brace rod 17 connecting its sides near its outer vertical 90 edges and connected with the bottom of the lower receptacle 4. In this manner the bottle is supported throughout its entire circumference, and the lower receptacle is also supported and rigidly connected with the 95 bottle support and in such a manner that the relative position of these two parts of the reservoir is always maintained. This construction and arrangement also does away with the use of upwardly extending 100 arms or other supporting means for the upper tank extending from the lower receptacle, whether connected with the frame of the stove or depending entirely upon the lower receptacle for support, and substitutes 105 new, simpler and more dependable supporting and connecting means. The supporting shields 15, 15^a and 15^b are semi-cylindrical

in form, and are formed of strong sheet metal so that they will resist all shocks and strains, and will at the same time form a shield for the lower part of the glass bottle 5 and the entire lower receptacle. If desired they may be made cylindrical so as to extend entirely around these parts.

The supporting shields may be connected with the oil supply pipe 9, and where they 10 do not extend to the supporting surface of the stove should be so connected, by means of a depending bracket 18 bolted or otherwise secured to the shield and having an aperture through which the pipe passes before joining the lower receptacle 4, by this 15 construction all the other fixed parts of the stove may be assembled with the hanger 18 strung on the pipe 9, and the shield then placed in position and secured by bolting 20 to the bracket 18 and the upturned ends of the rod 17. This not only facilitates the assembling operation but insures strength 25 and accuracy of adjustment.

When it is desired to connect the lower 25 receptacle with the frame of the stove, a bracket 19, is riveted or otherwise secured to the said receptacle and has the ends of its two arms bolted to the end plate 20 of the 30 stove frame. In this case open slots 21 extending from the lower end of the shield to a point substantially coincident with the top 35 of the bracket 19 are provided, these slots not only permitting the shield to be slipped over the brackets but provide an additional support and positioning means for the reservoir parts.

It will be understood that the shields 15^a and 15^b may if desired be made to extend to the floor or other supporting surface of 40 the stove, and that other changes in the details of construction may be made without departing from the scope of the invention.

It will also be apparent that the construction herein described and shown leaves the 45 upper edges of the receptacle or subcan-

entirely free from complex parts, making it easier to clean and giving it a cleaner and neater appearance, and that it gives a simpler, stronger and more positive and dependable connecting and supporting structure.

What we claim is:

1. In combination with an upper tank or reservoir in the form of a bottle inverted in normal position and a lower receptacle in which the extremity of said bottle is received, of a supporting and positioning structure for the said tank and receptacle comprising a member separate from the stove itself secured at the lower outer part of the said receptacle, extending upwardly above the same and spaced from its sides and top and having an annular portion at its upper part engaging the said bottle intermediate its top and bottom and supporting it against vertical and lateral movement bodily.

2. In the combination of mechanisms specified in claim 1 the upper portion of the receptacle being disconnected from the other parts and having no extending or connecting members.

3. In the combination of parts specified in claim 1 a support for the said connecting and supporting member comprising a pipe extending upwardly to the lower part of the receptacle and a connection between said pipe and said member.

4. In the combination of parts specified in claim 1 additional supporting means connected with the receptacle extending beyond the same and said member and adapted to be there secured to the frame of the stove.

Witness our hands this 18th day of December, 1923, at the city of Milwaukee, in the county of Milwaukee, State of Wisconsin.

WALTER C. LINDEMANN.
GUSTAVE C. LORENZ.
